UNITED STATES PATENT OFFICE.

GEORGE WALKER, OF CARNEGIE, PENNSYLVANIA, ASSIGNOR OF ONE-THIRD TO JOHN BURNSTIEL, OF CARNEGIE, PENNSYLVANIA, AND ONE-THIRD TO MILTON ZEUGSCHMIDT, OF PITTSBURG, PENNSYLVANIA.

CURTAIN AND POLE HOLDER.

No. 882,853.

Specification of Letters Patent. Patented March 24, 1908.

Application filed November 11, 1907. Serial No. 401,606.

To all whom it may concern:

Be it known that I, GEORGE WALKER, a resident of Carnegie, in the county of Allegheny and State of Pennsylvania, have invented a new and useful Improvement in Curtain and Pole Holders; and I do hereby declare the following to be a full, clear, and exact description thereof.

My invention relates to a combined curtain and pole holder, and has for its object to provide a cheap, simple and efficient device which can be applied to the ordinary form of pole bracket for clamping the pole, curtain or both within the same in a rapid and easy manner.

My invention consists, generally stated, in the novel arrangement, construction and combination of parts, as hereinafter more specifically set forth and described and particularly pointed out in the claims.

To enable others skilled in the art to which my invention appertains to construct and use my improved curtain and pole holder, I will describe the same more fully, referring to the accompanying drawing in which:

Figure 1 is a front elevation of a curtain pole supported by brackets embodying the invention. Fig. 2 is a side elevation of my improved curtain and pole holder. Fig. 3 is a longitudinal central section of the holder. Fig. 4 is a top or plan view of the same.

As illustrated in the drawing A represents the holder having the ordinary bracket 1, which is usually formed of thin sheet metal, and comprises the horizontal upper portion 2 and the inclined lower portion 3 bent from and connected to said portion 2 through the vertical portion 4, while such portions 2 and 3 are provided with the outwardly bent inner ends 5 for securing the bracket to the window frame B in the usual manner through nails or screws 6 passing through holes 7 in such ends 5. Mounted upon the upper face of the horizontal portion 2 is the adjustable member 8 which is provided with the usual curved arm 9 at its outer end for holding or supporting the pole D at the ends thereof and such member is adapted to be adjusted along said portion 2 and within the guides 10 riveted to said portion and bent over the member 8. A screw-bolt 11 passes through a hole 12 at the inner end of the member 8 and through

a slot 13 in the horizontal portion 2 of the bracket 1 and is provided with a nut 14 thereon for permitting said adjustment.

Mounted upon the adjustable member 8 is the pole and curtain support or clamp 15 which is longitudinally adjustable in said member by being slidably mounted thereon through a bar 16 fitting loosely within guides 17 bent up from said member, and interposed between the rear guide 17 and shoulders 18 on said bar is a spiral spring 19. Secured to the front end of the bar 16 is the curved bearing plate 20, which extends out from each side of said bar and is adapted to engage with the curtain C around the pole D or both, as hereinafter described. The rear end of the sliding bar 16 has pivoted thereto at 21, the locking lever 22, which has the rear or free end of the same bent up to form the thumb or handle portion 23, and such lever has a hole 24 within the same for the reception of a tongue or lug 25 bent up from the member 8 to lock the clamp 15 in its rearward or disengaging position.

The use and operation of my improved curtain and pole holder is as follows:—One of the holders A is placed on each side of the window frame B and one with the curved arm 9 omitted therefrom, as shown in Fig. 3, is placed centrally of said frame, so that when so placed the holders are secured to said frame by nails or screws 6 passing through the ends 5 on the portions 2 and 3 of the brackets 1 thereof. The pole D with its curtain C around the same is placed within the curved arm 9 on the member 8 of the end or side holders A after the bar 16 in each of the holders A is drawn or pushed back to the position shown in full lines in Fig. 2, where it is held in such position by the lug 25 on the member 8 fitting within the hole 24 of the lever 22 and has caused the compression of the spring 19 around said bar between the shoulders 18 thereon and the rear guide 17. When the pole D and curtain C have been set or adjusted to the proper position on the holders A as to the frame B they can be held in place, supported and clamped in said holders by pushing the lever 22 back slightly on each of the bars 16, and raise the same on each of the bars 16, which will thereby draw back its bar 16 and

release said lever from engagement with the lug 23, so that the spring 19 around each of said bars being thus relieved of its tension will throw the said bars 16 forward through 5 the guides 17, as well as their levers 22. This will cause the plates 20 at the front ends of the bars 16 in the side holders A to engage with and clamp the said curtain C and pole D between the same and the curved 10 arm 9 on said holders, while the plate 20 on the bar 16 in the center holder A will clamp said curtain against said pole at its central point or connection between the two parts of said curtain.

25 It will be evident that the member 8 and clamp 15 carried on the holders A can be adjusted on the bracket 1 in the ordinary manner through the bolt 11 and nut 14 working in connection with the slot 13 in said 30 bracket portion 2, so that the curtain C and pole D can be set in the position described with relation to the window frame B or its window b, and that various modifications and changes in the design and operation of 35 the parts of my improved curtain and pole holder may be resorted to without departing from the spirit of the invention or sacrificing any of its advantages.

It will thus be seen that my improved 40 curtain and pole holder is one that contains few parts and permits of easy and rapid operation, while at the same time the curtain and pole will be clamped together and within the holder quickly and rigidly, so that 45 there will be no liability of their becoming separated or out of position through the ordinary conditions. The parts of the holder are strong and durable and are not liable to get out of order or separated, while

the movements of the parts are positive and 40 convenient at all times.

What I claim as my invention, and desire to secure by Letters Patent, is:—

1. In a curtain and pole holder, the combination with the bracket, of a supporting 45 member, and a spring operated sliding bar on said member for clamping the curtain and pole.

2. In a curtain and pole holder, the combination with the bracket, of a supporting 50 member, and a spring operated sliding bar on said member adapted to be held and released for clamping the curtain and pole.

3. In a curtain and pole holder, the combination with the bracket, of a supporting 55 member, a spring operated sliding bar on said member, and means for holding said bar and for releasing the same to permit the clamping of the curtain and pole.

4. In a curtain and pole holder, the combination with the bracket, of a supporting 60 member, a spring operated sliding bar on said member, and a lever on said bar and adapted to engage with said member for holding said bar.

5. In a curtain and pole holder, the combination with the bracket, of a supporting member, a spring operated sliding bar on 65 said member, a hand lever pivoted to said member, a bar having a hole within the same, and a lug on said member and fitting within said hole for holding said bar.

In testimony whereof, I, the said GEORGE WALKER, have hereunto set my hand.

GEORGE WALKER.
